UNITED STATES PATENT OFFICE

WALTHER RASTER, OF CHICAGO, ILLINOIS, ASSIGNOR TO JUSTRITE MANUFACTURING COMPANY, OF CHICAGO, ILLINOIS, A CORPORATION OF ILLINOIS

LAMP-ATTACHING DEVICE FOR MINERS' CAPS

Application filed December 12, 1927. Serial No. 239,406.

The invention has for its object to provide an attachment for a miner's cap for cooperation with a fitting on a lamp to be attached to the cap which will permit the lamp to be readily attached to and detached from the cap; will provide means whereby the lamp is held firmly in place on the cap when attached thereto and which will obviate discomfort to the wearer of the cap by reason of the presence, as heretofore, of a projection so positioned as to occasion discomfort to the wearer of the cap when the lamp is attached thereto.

A further object of the invention is to provide an attachment for the cap which, in sale, constitutes a detachable part of the lamp and may be easily mounted on the cap by the purchaser.

The invention, while preferably embodied in an attachment of the type indicated in the last preceding paragraph, may also be embodied in an attachment which may be incorporated by the manufacturer of the cap as a permanent, non-detachable element of the latter to receive lamps equipped with the companion element.

In the accompanying drawings illustrating the invention:

Figure 1 is a fragmentary vertical section of a miner's cap equipped with a lamp carrying attachment constructed in accordance with the invention.

Figure 2 is a perspective view of the lamp supporting member of the cap equipped with the lamp carrying attachment of the preferred form of embodiment of the invention also shown in Figure 1.

Figures 3 and 4 are sectional views on the lines 3-3 and 4-4, respectively of Figure 1.

Figure 5 is a fragmentary perspective view of the body of a lamp equipped with means cooperating with the lamp carrying attachment for securing the lamp to the latter.

Figure 6 is a view similar to Figure 2 but illustrating an embodiment of the lamp carrying attachment adapted for permanent association with the lamp supporting member.

Figure 7 is a view similar to Figure 2 showing another embodiment of the invention.

Figure 8 is a section on the line 8-8 of Figure 6.

Figure 9 is a section on the line 9-9 of Figure 7.

Figure 10 is a sectional view similar to Figure 8 illustrating a modified form of construction.

Figure 11 is a view similar to Figure 5 showing the lamp body equipped with a device for coaction with the structure shown in Figure 10.

The lamp supporting member 1 of the cap 2 consists, usually, of sheet metal and fibre board. This member comprises a middle portion and two oppositely extending end flanges 3 and 4, one of which is rigidly secured to the visor 5 of the cap and the other to the crown. The sheet metal is usually very thin and is provided with side flanges 6 which are folded in part to lie upon the body portion 7 and in part to secure a piece of fibre board to the middle portion of said member, said portion being provided with a relatively large opening 7 near the upper end thereof and with a slot 8 which intersects the bend at the inner end of the flange 4.

Lamps, such as the acetylene type, have been provided with hooks to engage in the slots 8 and, in some instances, with spring clamps for engaging the side edges of the middle portions of the members 1, and, by reason of the fact that the hooks are relatively large, the points thereof are apt to press against the foreheads of wearers of the caps and are annoying. The aforesaid means for attaching the lamps are also deficient in that the lamps are not very firmly held in place thereby.

The present invention is designed to overcome the defects and objections incident to the substantially conventional attaching means now commonly used as above described and, in order that the attaching means may be applied to existing caps, an important element of the present invention lies in providing means which are adapted for association with the lamp supporting member of the cap by the purchaser of the lamp and its companion carrier.

The lamp carrier shown in Figures 1 to 100

4 inclusive, comprises a sheet metal member which includes the flat middle portion 9 having a longitudinal slot 10 midway between its side edges. This slot is bordered at the sides by guide flanges 11 bent to extend outwardly and having their free portions spaced from and parallel with the middle portion 9. This portion 9 is curved between its ends and terminates at its upper end in the flange 12 which overhangs but is spaced from the flange 4 of the member 1. The said portion 9 and flange 12 are provided at their side edges with the tongues 13 and 14, respectively, which are slightly offset therefrom, the free end portions of said tongues being easily bent, digitally, about the side edges of the member 1 and its flange 4, respectively, and are shown so bent in the drawings, but, when delivered to the consumer, are straight. The tongues 13 and 14 cooperate with each other and the portions of the member 1 engaged thereby to very firmly secure the member 9 to the member 1 while maintaining the former offset from the latter. This is rendered necessary in instances where the members 1 of caps are equipped with certain recently introduced devices for attaching electric lamps to the caps.

The free portions of the guide flanges 11 are not quite as long as the slot 10 but are cut away in part to provide guide ribs 15 which are slightly convergent. The lamp body 16 is provided at the back with a pair of guide flanges 17 which, preferably, constitute inturned side edge portions of a plate 18 secured to the lamp body 16 and are spaced and arranged so that their free portions will engage under the free portions of the flanges 11 to provide a snug fit. The guide ribs 15 are adapted to act as leads to enable the wearer of the cap to more easily associate the lamp with the member 9. The length of the lamp is such that when attached to the member 9 its bottom rests upon the flange 3 of the member 1 as shown in Figure 1, said flange thus providing a stop formation cooperating with the flanges 11 to hold the lamp in place.

The embodiment shown in Figure 6 differs from that shown in Figures 1 to 4 inclusive in that the portions of the tongues which, in Figures 1 to 4 are shown bent about the side edges of the member 1 and its flange 4, are omitted, the terminals of said tongues 19 being clamped between the member 1 and its flange 4 and the side flanges 6 folded over upon said parts, this form of embodiment being adapted to be supplied to the manufacturer of the caps for incorporation into the same.

It will be obvious that the function of the flange 12 of the member 9 and the tongues 14 thereof, is to hold said member 9 against longitudinal movement relatively to the member 1. In Figures 7 and 9, I have shown an embodiment wherein said flange 12 and

tongues 14 are omitted. In this embodiment I employ a plate 20 having tongues 21 the terminals of which are bent or folded over the side edges of the member 1 to hold the plate 20 against lateral movement. In the latter I provide a central opening 22 which is bordered by an annular flange 23 which engages in the opening 7 of the member 1 to hold the plate 20 against longitudinal movement relatively to the member 1.

Integral with the plate 20 is a flange 24 which is provided with the slot 25, side flanges 26 and guide ribs 27 which correspond to the slot 10, flanges 11 and guide ribs 15, respectively, of the embodiment shown in Figures 1 to 4 inclusive. The flange 24 is bent between its ends as at the point 28 to extend substantially parallel with the plate 20, the latter being further provided at its lower end with a flange 29 which is folded over upon the lower end of the flange 24 for obvious reasons.

It will be obvious also, without specific illustration, that the structure of Figures 7 and 9 may be modified by cutting away the terminal portions of the tongues 21 extending over the side edges of the member 1 and the edges of the shorter tongues confined between the member 1 and its side flanges 6 as in the embodiment shown in Figures 6 and 8.

In the embodiment shown in Figures 10 and 11, which concerns only the interengaging flanges on the lamp and its carrier, the carrier 30 is shown as being of the type of Figures 1 to 4 inclusive and is provided with the slot 31 corresponding to the slot 10 of Figures 1 to 4, said slot being bordered by the L-shaped flanges 32 the free or outer portions of which project over the side portions of said slot 31, the lamp body being provided with outwardly extending flanges 33 for interengagement with said flanges 32.

The assembled structure of Figures 1 to 4 and that of each of the remaining figures showing other or modified embodiments, is, broadly, in each instance the substantial equivalent of a lamp supporting member equipped with lamp engaging means integral with or permanently associated therewith, it being obvious that ordinary skill in mechanics will suffice to enable the artisan to so embody the invention without further specific illustration.

I claim as my invention:

1. Means for detachably associating a lamp with a miner's cap equipped with a conventional lamp supporting device, comprising a sheet-metal member equipped along its side edges with integral bendable tongues having their terminal portions folded over the side edges of said device, there being interengaging formations on the latter and said sheet-metal member other than said tongues for co-action with the latter to hold said sheet-metal member against movement relatively to said supporting device in any direction, a lamp,

and interengaging devices on said lamp and said sheet-metal member for detachably associating the latter with said lamp.

2. Means for detachably associating a lamp with a miner's cap equipped with a conventional lamp supporting device, comprising a sheet-metal member equipped with elements engaged with the said supporting device for holding said member against lateral and longitudinal movement thereon, a pair of parallel substantially vertically disposed guide members on said sheet-metal member, a lamp, and a pair of similar guide members on said lamp arranged for sliding engagement with the guide members on the sheet-metal member for detachably interlocking said lamp with the latter.

3. Means for detachably securing a miner's lamp to a conventional miner's cap equipped with a flat, substantially Z-shaped device secured at one end portion to the visor and at its other end portion to the crown of said cap, said means comprising a substantially L-shaped flat sheet-metal member equipped at opposite end portions along its side edge with tongues folded over the side edges of the middle portion of said device, there being an elongated slot midway between the side edges of that portion of said member opposing the middle portion of said device, L-shaped flanges bordering the sides of the slot and converging toward each other at one end of said slot, and a member rigidly mounted on the lamp equipped with similarly spaced and converging L-shaped flanges for engaging the flanges of the said member for firmly and detachably associating the lamp with the cap.

WALTHER RASTER.
